DESIGN FOR A DRESS ENSEMBLE

Marie Eileen Smith, New York, N. Y.

Application January 17, 1938, Serial No. 74,336

Term of patent 3½ years

To all whom it may concern:

Be it known that I, Marie Eileen Smith, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The characteristic feature of my design resides in the combination in the ensemble disclosed of the jacket member, which features the specific applique and raffia embroidery on the front as shown.

I claim:

The ornamental design for a dress ensemble, substantially as shown, and described.

MARIE EILEEN SMITH.
